UNITED STATES PATENT OFFICE.

BENJAMIN C. VANDUZEN, OF CINCINNATI, OHIO, ASSIGNOR TO HERBERT D. LAFFERTY, OF NASHVILLE, TENNESSEE, AND STANLEY B. LAFFERTY, OF DAVENPORT, IOWA.

PUMP.

SPECIFICATION forming part of Letters Patent No. 268,845, dated December 12, 1882.

Application filed April 29, 1882. (No model.)

To all whom it may concern:

Be it known that I, BENJAMIN C. VANDUZEN, of Cincinnati, Hamilton county, Ohio, have invented certain new and useful Improvements in Pumps, of which the following is a specification.

The object of my invention is to simplify the construction of pumps without rendering them less efficient in operation; and it relates more particularly to that class of pumps which are suspended in the well, and in which the pumping-cylinder is located at one side of the pump-stock.

15 The principal feature of my invention relates to such a construction and arrangement of parts as will permit of a ready removal of the pumping-cylinder, together with the various valves, for the purposes of repairing or replacing any of such parts.

20 The various other features of my invention will be apparent from the following description and the drawings, in which—

Figure 1 represents an elevation of my invention, partly in section, showing one form 25 of joint connecting the various parts. Fig. 2 represents a transverse section of the pumping-cylinder and vacuum-chamber, taken at the line $x-x$ of Fig. 1, showing the construction and arrangement of the lower valve. Fig. 3 30 is a side elevation of the upper part of the pump. Fig. 4 is a central longitudinal section through the pumping-cylinder, vacuum-chamber, and discharge-pipe, showing the preferred construction of the joints between the various parts.

A is the body or support of the pump, and consisting of the base a and the hollow pillar a' , the two being connected by a suitable brace, as a^2 . Through this pillar a' passes the discharge-pipe B, which is prevented from moving longitudinally therein by the keys b, which enter apertures in the pillar a' , made for their reception, and when the keys are driven into position they impinge against the pipe B, preventing any longitudinal movement.

On the top end of the discharge-pipe B is screwed the head or top B', which is provided with a spout, b' , and the brackets b^2 , between which the handle C is pivoted.

If desired, an ornamental casing, C', may be 50 placed around the discharge-pipe B, between the pillar a' and the top B'.

To the lower end of the discharge-pipe B is screwed the casting D, in which is formed the vacuum-chamber d, a partition, d' , preventing 55 any communication between the upper end of said chamber and the discharge-pipe B. The lower part of this casting D is provided with a curved tubular projection, D', the upper end of which may be provided with a circular shoe 60 or seat, E, or preferably, as is shown in Fig. 4, with a circular head, D². The upper end of the casting D, above the partition d' , is provided with a curved lateral passage, E'.

In the lower end of the casting D is screwed 65 the suction-pipe F, which extends down into the well to the required distance.

The pumping-cylinder is formed in the casting G, and consists of the chambers $g g'$, in which operate the pistons $h h'$, which are connected to the pump-rod H, which latter is connected to the pump-handle C by the bolt I. The casting G is provided with a curved tubular projection or passage, G'. When the castings D and G are in position with relation to 70 each other the lower end of the casting G, being slightly flared, fits around the circular head D² on the projection D' of the casting D, the head being beveled to correspond with the flare in the end of the casting G, as shown in 75 Fig. 4. The end of the opening or passage through the projection G' is also flared, as shown in Fig. 4, and into this flared opening fits the head of the projection E' on the casting D. Both of these joints are rendered watertight by means of elastic rings or gaskets j, which fit into channels or grooves around the heads of the projections which fit into the flared openings, thus preventing the packing from being displaced. When the castings D 80 and G are connected and constructed as above described they occupy the position shown in Fig. 4. If preferred, however, the construction and arrangement shown in Fig. 1 may be employed. In this figure the projection D' of 85 the casting D is provided with a circular shoe or seat, E, into which the end of the casting G fits, and the end of the projection G' fits 90 95

into the mouth or opening of the passage E', elastic packing being interposed in each instance, as in the first-described construction. While the construction shown in Fig. 1 may 5 be advantageously employed, I prefer the construction shown in Fig. 4, for the following reasons, viz: The inner surface of the cylinders $g'g$ is bored out smooth and usually enameled, and by forming the lower end of the 10 casting G as shown in Fig. 1 the flaring lower end of casting may easily be enameled, or otherwise made smooth, and thus a tighter joint can be made than by the construction shown in Fig. 1.

15 The casting D, when formed as shown in Fig. 4, is more easily cast than when of the form shown in Fig. 1, as the shoe E makes a difficult point to "draw" from the sand. When formed as shown in Fig. 4 the valve-seat on 20 the end of the projection D' is more easily made smooth and even than when the casting is of the form shown in Fig. 1. The elastic packings j are not so liable to be disarranged when the castings are of the form shown in 25 Fig. 4 as when of the form shown in Fig. 1, as in the former case they remain with the casting D left in the well, and are not disturbed, while in the latter case they are lifted from the well with the casting G, and are liable to 30 be interfered with.

One end of a rod or tube, J, is screwed into the projection G' and extends upward nearly to the bracket or projection k, projecting from one side of the pillar α . Through this projection k passes a set-bolt, K, which is screwed 35 through said projection and rests in a depression in the end of the pipe or tube J, which latter is preferably made in the form of a tube, the interior of which communicates with the 40 interior of the passage G', as shown, in which event it serves the double purpose of an air-chamber and as a rod for keeping the various parts of the pump in position.

In very deep wells, where the pumping-cylinders are located a considerable distance 45 below the surface of the ground, it will be found desirable to place the bracket or projection k lower down—as, for instance, at some point below the ground—connecting it to the pipe B, 50 so that the distance between said bracket and the projection G' shall not be great.

In the lower end of the pumping-chamber g is placed the drop-valve L, which, when the casting G is in position, rests on the upper end 55 of the tubular projection D', which forms a valve-seat for said valve. The hinge of this valve is connected to a lug, l, projecting inwardly from an open ring, M, which latter is placed loosely in the end of the chamber g , 60 but is held therein by its own inherent elasticity. One or two other projections, m, extend inwardly from the ring M, and the valve L is provided at points immediately over these 65 projections with small lugs or wings n. By this construction, when the casting G is lifted the wings n on the valve will be above the pro-

jections m, and the valve will thus be prevented from dropping down.

The water is drawn up from the well through the suction-pipe F, the vacuum-chamber d 70 causing a more steady suction, and into the chamber g, from whence it passes through the piston h, a portion entering the chamber g' , and a portion passing out through passages G' and E' into the discharge-pipe B and out 75 through the spout b'. As the water passes through the passage G' a portion of it enters the pipe J, which, being closed at its upper end, acts as an air-chamber, which causes a steady flow of water from the discharge-pipe. 80

By the construction above described the pumping-cylinders and pistons and valves may be very easily lifted from the well, the only bolts necessary to be removed being the set-bolt K and the bolt I, connecting the pump-rod H to the handle C. When these bolts are removed the casting G, containing the pumping-cylinders and the various pistons and valves, may, by means of the pump-rod H and rod or pipe J, be lifted, the projection G' being lifted 90 from the projection E' and the lower end of the casting G from the projection D', and when the casting G is to be replaced in the well, to the position shown in the drawings, it is very easily accomplished, and when in this position is firmly held there by the set-bolt K, the gaskets or packing j preventing any leakage 95 between the pumping-cylinders and the casting D.

Having thus described my invention, what I 100 claim as new and of my invention, and desire to secure by Letters Patent, is as follows:

1. In a pump, the combination of a cylinder provided with a flaring mouth or end, and the cylinder-head or valve-seat beveled to fit said 105 flare, and an annular packing interposed between said flaring mouth and the head, substantially as and for the purposes specified.

2. In a pump, the combination of a cylinder provided with a flaring or trumpet-shaped 110 mouth or end, and the beveled or wedge-shaped cylinder-head or valve-seat having an annular groove around its periphery, and an annular packing located in said annular groove, substantially as and for the purposes specified. 115

3. In a pump, the combination of the wedge-joint with the end of the cylinder, and the edges of the cylinder-head or valve-seat, and a packing interposed and wedged between the adjacent opposing portions of said joint, substantially as and for the purposes specified. 120

4. In a pump, the combination of the wedge-joint with the end of the cylinder, and the edges of the cylinder-head or valve-seat, and a packing interposed and wedged between the adjacent opposing surfaces of said joint, and held in an annular groove in one of said opposing surfaces, substantially as and for the purposes specified. 125

5. In a pump, the combination of the pump-cylinder and the discharge-pipe, the two being connected by a hollow wedge-shaped joint 130

without extrinsic support, a suitable packing being located between the opposing surfaces of said joint, substantially as described.

6. In a pump, the combination of the pumping-chamber G and the discharge-pipe B, connected by the passages E' and G', these two passages being united by a wedge-shaped joint, and a suitable packing interposed between the opposing surfaces of said joint, substantially as and for the purposes specified.

7. In a pump, the combination of the pumping-chamber G, casting D, and the discharge-pipe B, the cylinder G being united to the passages D' and E' of said casting by wedge-shaped joints, substantially as described.

8. In a pump, the combination of two cylindrical or tube sections whose adjacent ends are formed, one with a beveled edge and the other flared to fit over and wedge, forming a joint without extrinsic support, upon the beveled edge, and an annular packing located in a groove near the end of one of the sections and wedged between the adjacent surfaces of said ends, substantially as and for the purposes specified.

9. A pump consisting of a discharge-pipe suitably supported, its lower end having connected thereto the casting D, in combination with the pumping-cylinder placed at one side of said discharge-pipe B, and held firmly in position by the single rod J, for enabling the cylinder to be lifted without disturbing the discharge-pipe, substantially as and for the purposes specified.

10. The combination of the pumping-cylinder G, provided with the passage or projection G', and the casting D, provided with the passages D' and E', said pumping-cylinder and casting being held in position with rela-

tion to each other by the tube J and set-bolt K, substantially as and for the purposes specified.

11. The combination of the casting D, provided with the vacuum-chamber d, separated from the discharge-pipe by the partition d', and the pumping-cylinder G, connected to said casting and retained in position by the tubular air-chamber J and set-bolt K, substantially as and for the purposes specified.

12. In a pump, the body A, consisting of a hollow pillar, a', suitably braced, in combination with the discharge-pipe B, held in position in said body by the keys b, and the valve-seat below the ring, substantially as described.

13. The combination of the pumping-cylinder g and the valve L, said valve being located within and connected to the lower edge of a ring, M, retained in the lower end of said pumping-cylinder, substantially as and for the purposes specified.

14. The combination of the ring M and the valve L, connected thereto, said ring being provided with the projections or lugs m, and the valve being provided with the wings n, substantially as and for the purposes specified.

15. In a pump, the combination of two cylindrical or tube sections, the end of one flared to fit over and wedge upon the adjacent end of the other, and an annular packing wedged between the adjacent surfaces of said ends, and a provision located upon one of said adjacent inclined surfaces for holding the packing in position when the sections are separated, substantially as and for the purposes specified.
